UNITED STATES PATENT OFFICE.

TRACY V. BUCKWALTER, OF CANTON, OHIO, ASSIGNOR TO TIMKEN ROLLER BEARING COMPANY, OF CANTON, OHIO, A CORPORATION OF OHIO.

METHOD AND MECHANISM FOR FINISHING ROLLS.

1,373,051.

Specification of Letters Patent. Patented Mar. 29, 1921.

Application filed January 28, 1918. Serial No. 214,068.

To all whom it may concern:

Be it known that I, TRACY V. BUCKWALTER, a citizen of the United States, residing at Canton, in the county of Stark and State of Ohio, have invented an Improved Method and Mechanism for Finishing Rolls, of which the following is a specification.

This invention has as its primary object to finish rolls to the true form desired in a simple manner and more particularly to obtain superior rolls inexpensively through a single burnishing operation producing true form, especially for conical bearing rolls having several bearing surfaces.

In the manufacture of bearing rolls, it has been usual heretofore to obtain the approximate form desired by means of a machine tool, then hardening and thereafter grinding the hardened rolls as closely as practicable to the desired surfaces, but the accuracy of surfaces and dimensions that are desirable cannot be obtained by grinding. Where several grinding operations are required, as in the conventional method of finishing the peripheral and end surfaces of a roll, the work is expensive and it is not practicable to obtain the concentricity of surfaces which it is important to obtain in a roll, there being usually slight eccentricities in the rolls which prevent uniform rolling action, produce unequal distribution of loads, and result in the chipping of the corners of the rolls, particularly before the rolls of a set have worn down to take their due proportions of the load or where the load is not equally distributed.

As conical bearing rolls are required to carry radial and thrust loads, it is important that the conical surface or surfaces which take the thrust loads shall be concentric with respect to the conical surface or surfaces which take the radial loads, as well as that they shall be true conical surfaces, since otherwise the rolls will be thrown away from their correct relation, they will not contact along the true cone elements, the desired uniformity of action will not be obtained, the bearings will be further distorted, and breakage will result which otherwise would be avoided.

In accordance with my invention, in the application thereof here illustrated, each roll is provided with three peripheral surfaces of conical form, the cone elements of the surface at the smaller end of the roll

forming a larger angle and the cone elements of the surface at the larger end of the roll forming a smaller angle with the axis than the cone elements of the intermediate conical surface forming the bulk of the periphery and designed for carrying the radial load initially, and in addition thereto the rolls are provided with truncated ends having conical surfaces adapted for taking thrust loads, such end surfaces being concentric with the respective peripheral surfaces adapted for taking the radial loads and formed by the same mechanism simultaneously therewith.

The rolls thus finished by burnishing are not only true but the rolling operation between hard steel dies, to which they are subjected, has a refining influence not obtained by the cutting action of a grinding wheel, such burnished rolls having a superior surface quality in the texture of the metal.

While the primary object is the production of true bearing rolls of closer uniformity and better wearing qualities, it will be understood that these characteristics are useful in other relations, as in steel pins for various uses.

The nature and characteristic features of my invention are fully disclosed in the following description and the accompanying drawings in illustration thereof.

In the drawings, Figure 1 is an elevation of a machine comprised in my invention; Fig. 2 is an elevation of the same at right angles to the position shown in Fig. 1; Fig. 3 is a broken sectional view on an enlarged scale; taken on the line 3-3 of Fig. 1; Fig. 4 is a broken sectional view, taken on the line 4-4 of Fig. 3; Fig. 5 is an irregular sectional view, taken on the line 5-5 of Fig. 3; Fig. 6 is a side elevation of the spacing rings; Fig. 7 is a sectional view on an enlarged scale showing the dies separated, the finished rolls discharging through the bed, the cage descending to receive the succeeding set of green rolls, and the feed gear rising to deliver thereto the set of green rolls which it carries; Fig. 8 is a profile of the master die; and Fig. 9 is a sectional view through a cup and cone having between them rolls finished in accordance with my invention.

The machine illustrated comprises a housing 1 provided with a bed 2 in which is

fixed a circular steel die 3 having a shoulder 4 and a hardened conical face 5.

A revoluble head 6 has fixed thereon a circular steel die 7 having the face 8 composed of the concentric hardened conical surfaces 8', 8^a, 8^b and 8^c concentric with the surface 5 and conforming to the surfaces of the rolls which are to be burnished by rolling them between the dies.

16 The head 6 has the conical bearing surface 9 within its die 7 and the oppositely inclined conical bearing surface 10 within its ring 11, which surfaces engage the respective conical rollers 12 and 13 bearing 15 on the respective oppositely inclined cones 14 and 15 fixed on a sleeve 16, such bearings maintaining the alinement of the head as well as reducing friction in the revolution thereof.

20 The sleeve 16 makes a slip fit with and is movable vertically on a column 17 fixed in the bed 2, and is adapted to rest on the spacing rings 18 and 19 carried by the bed. These rings have the respective inclined or 25 helical surfaces 20 and 21 for adjusting the elevation of the ring 19 by turning the ring 18, thereby adjusting the elevation of the parts 16 and 6, with their connections, and the final relation of the die 7 to the die 3 30 for finishing the burnishing of rolls of different sizes. The ring 18 is turned by means of the worm segment 22 thereon and the engaging worm shaft 23 journaled in the bed 2, the adjustment being made by means of a 35 micrometer 24 to effect diameter changes within .00025" which is desirable for varying diameters to avoid the necessity for extreme accuracy in grinding cups and cones.

The head 6 is revolved continuously at a 40 comparatively high speed by means of a helical gear 25 fixed thereon and engaging a helical gear 26 fixed on the shaft 27, the latter being journaled in the housing and driven by a sprocket wheel 28.

45 A shaft 29, journaled in the housing and driven by a pulley 30, is provided with a worm 31 which drives, at a comparatively low speed, a worm wheel 32 fixed on a shaft 33, the latter being journaled in the 50 housing. The shaft 33 has fixed thereon the cams 34 and 35 and the beveled gear 36, for effecting the following operations in synchronized relation.

The cam 34 engages a roller 37 in the lower 55 end of a rod 38 having a free movement vertically in the column 17 through which it extends. The rod 38 is connected by a cap 39 with the sleeve 16, which is adapted to be elevated thereby, to elevate the head 6 with its die 7 and the cage 40 having the seats 41 for holding the rolls between the dies; the sleeve 16 having a lip 16' which, at a proper point in its upward movement, engages and elevates the cage to release (fol- 60 lowing the withdrawal of the die 7 there-

from) the finished rolls held thereby, permitting them to drop through the conduits 2' of the bed into the trough 42 for receiving them as well as the oil in which they are burnished. A guard 42' catches the 70 splash of oil from the rolls in process of burnishing and directs it to the trough, whence it is drained off and returned to the rolls in process of treatment.

A coiled spring 43, which bears against a 75 seat 44 adjustable in the housing and a seat 45 adjustable along the rod 38, acts through the rod on the sleeve 16 and the connected head 6 to apply the necessary pressure to the rolls in process of burnishing between the 80 dies 3 and 7, the desired tension of the spring being obtained by turning down the seat 44 or adjusting the seat 45 by turning up the nut 46 supporting it on the rod.

The cams 35 act upon levers 47 having 85 the fulcrums 48 and being connected with the rods 49, which are reciprocated thereby through the bed 2. The feed gear 50 is elevated by the upward movement of these rods to a height which is adjustable by 90 adjusting the nuts 49' connecting the levers with the rods.

The beveled gear 36 engages a bevel pinion 51 fixed on a shaft 52 which is journaled in the housing; the shaft having a gear 95 wheel 53 fixed thereon which engages the feed gear 50 and revolves it on the bed 2.

The feed gear 50 is provided with the seats 50' approximately the length of a roll and arranged in a conical ring around the 10 shoulder 4 on the die 3 to which the green rolls are delivered from a chute 54, the feeding being facilitated by vibrating the chute in any suitable manner.

The finished roll 55 has the conical surface 55' at its larger end for taking up 11 thrusts against the lip 56' of the cone 56 (Fig. 9) and the conical peripheral surface 55^a, extending say three-fourths of the roll length, for carrying the initial radial load 1 transmitted between the cone 56 and the 11 cone 57. The periphery of the roll has the conical surface 55^b at the smaller end, with a slightly greater inclination to the axis of the roll than the surface 55^a, and the conical 1 surface 55^c at the larger end, with a slightly smaller inclination to the axis than the surface 55^a. The reduced surfaces 55^b and 55^c are formed to throw initially the radial load wholly on the intermediate surface 55^a 1 and avoid the undesirable effects of inaccuracies of workmanship, as a result of which radial loads are unequally distributed and improperly imposed upon the end of the roll before the component parts of the bearing are worn to distribute the load properly.

In the operation, with the mechanism in the position illustrated in Fig. 3, the head 6 is revolved at a comparatively high speed, by its driving mechanism described, and its 1

die 7 is revolved thereby in contact with rolls 55 held on the die 3 by the cage 40, whereby the rolls are revolved and burnished under a pressure adjustable by means of the 5 spring 43. Simultaneously with the revolution of the head 6 and the burnishing of the rolls, the feed gear 50 is revolved slowly on the bed 2, by its driving mechanism described, and green rolls are delivered from 10 the chute 54 to the seats 50' of such gear, which is fully charged thereby. When the head 6 has traveled through the number of revolutions necessary for burnishing the sets of rolls between the dies, the cam 34 elevates the connected rod 38, sleeve 16 and 15 head 6, as also the die 7 and cage 40, so as to free the finished rolls, which drop from the face of the die 3 through the conduits 2' into the trough 42. As the cam 34 continues its 20 revolution, the parts 38, 16 and 6 descend, the cage 40 moving down therewith until engaged by the bed 2 and die 3 in the downward movement of the die 7, which is held temporarily or caused to dwell in such movement 25 by reason of the shape of the cam 34 to permit the delivery of the rolls to the cage. Simultaneously with this arrested downward movement, the cams 35 act through the levers 47 on the rods 49 to elevate 30 the feed gear 50, which delivers the green rolls carried thereby upon the surface of the die 3, in the pockets of the cage 40. The continued revolution of the cams 34 and 35 brings the die 7 into contact with the 35 green rolls and lowers the gear 50 on the bed 2, for receiving its further charge of green rolls while its previous charge is being burnished.

The burnished rolls are then hardened and 40 ready for use.

Rolls finished in this manner may be truncated in the manner described because in 45 rolling them between dies there is no necessity for the usual end construction required for holding and revolving them in contact with a grinding wheel.

It is to be understood that the term bearing as used in the claims comprehends devices other than anti-friction rollers, as pins 50 for holding parts together.

Having described my invention, I claim:

1. The combination with a die having a 55 conical surface, of a die having a plurality of conical surfaces concentric with said surface first named, and means for revolving one of said dies with relation to the other.

2. The combination with a pair of dies 60 adapted for consolidating and burnishing roll surfaces, of means for revolving one of said dies relatively to the other, and means for moving one of said dies toward and from the other.

3. The combination with a stationary die 65 having a conical surface, of a second die having a conical surface concentric with said

surface first named, and means for revolving said die second named and moving it toward and from said die first named.

4. The combination with a die having a conical surface, of a second die having a 70 conical surface concentric with said surface first named, revoluble mechanism to which said second die is fixed, and a reciprocatory device for supporting and altering the position of said mechanism to adjust the relation of said second die to said die first named. 75

5. The combination with stationary mechanism comprising a die having a conical surface, of revoluble mechanism comprising a die having a conical surface concentric with 80 said surface first named, a reciprocatory mechanism supporting said revoluble mechanism in adjustable relation to said stationary mechanism, and adjustable means for limiting the movement of said reciprocatory 85 mechanism and the space between said dies.

6. The combination with mechanism comprising a die and a column, a sleeve movable longitudinally on said column, a head revolvable about said sleeve, and a die fixed to said 90 head and adapted to coact with said die first named in burnishing rollers.

7. The combination with mechanism comprising a stationary die having a conical surface, supporting means concentric with said 95 surface, mechanism for reciprocating said means in the direction of the axis of said surface, and revoluble mechanism carried by said means and comprising a die having one or more conical surfaces concentric with said 100 surface first named.

8. The combination with a bed and a die fixed thereto, of means for holding rollers on said die, means for feeding rollers to said means first named, mechanism comprising a 105 die adapted to coact with said die first named upon rollers held by said means first named, and mechanism for revolving said mechanism first named and reciprocating it with relation to said bed to change the distance 110 between said dies.

9. The combination with a bed and a die fixed thereto, of mechanisms movable to and from said die for holding and releasing devices to be burnished thereon, mechanisms 115 movable with relation to said die for feeding said devices to said die, mechanisms for moving the mechanisms aforesaid in synchronous relation, and a revoluble device and a die fixed thereto for coacting with said die 120 first named in burnishing said devices.

10. The combination with a stationary die, of a feeding device adapted to revolve and reciprocate with relation to said die, a second die, and means for revolving and reciprocating 125 said second named die with relation to said first named die.

11. The combination with a bed, of a feeding device journaled and movable transversely on said bed, a revoluble shaft, and 130

means whereby said shaft revolves said device and moves it transversely.

12. The combination with a bed, of a feed gear journaled and movable transversely relatively to said bed, a revolute shaft, mechanism comprising gears whereby said shaft revolves said gear, and mechanism comprising a cam and a rod whereby said shaft moves said gear.

10 13. The combination with a bed provided with a die and means for holding articles on said die, of a revolute and transversely movable device for feeding said articles to said die and holding means, a revolute shaft, means whereby said shaft revolves said device, and means whereby said shaft elevates said device.

14. The combination with mechanism comprising a stationary die, of a revolute and 20 transversely movable device for feeding articles to said die, reciprocating mechanism for holding said articles on said die, a revolute shaft, means whereby said shaft revolves said device, and means whereby said shaft 25 elevates said device and mechanism in synchronous relation to deliver articles to and discharge them from said die.

15. The combination with mechanism comprising a revolute and transversely movable 30 feeding device, a holding device, a revolute head, reciprocating mechanism for carrying said head and moving said holding device, a revolute shaft, means whereby said shaft revolves said feeding device constantly, means whereby said shaft elevates said feeding device intermittently, and means whereby said shaft operates said reciprocating mechanism intermittently.

16. The combination with a bed and a column fixed thereon, of a sleeve movable longitudinally on said column, a rod movable through said column to move said sleeve, means comprising a spring acting on said rod to apply pressure to said sleeve, a head 45 revolute on said sleeve, a bed, a feeding device revolute and movable transversely with relation to said bed, a cage for holding articles between said bed and head, a revolute shaft, means whereby said shaft operates

said rod to move said sleeve longitudinally, means whereby said shaft moves said device transversely, and means whereby said shaft revolves said device.

17. The combination with a bed provided with a conical die and conduits for articles 55 discharged from said bed, of a revolute head provided with a conical die adapted for coöperation with said die first named, and means for moving said revolute head axially with relation to said bed.

18. The combination with a bed provided with a conical die, of a cage for holding articles on said die, a revolute head provided with a conical die adapted for coöperation with said die first named, supporting means 65 on which said head is revolute, means for moving said supporting means in the direction of the axis of revolution of said head, and means for regulating the distance said head is movable toward said bed.

19. The combination with mechanism comprising a bed, of mechanism comprising a revolute head adapted to coöperate with said bed, and mechanism comprising a revolute device having an inclined surface for 75 regulating the relation of said head to said bed.

20. The combination with a bed provided with a die, of a revolute head provided with a die adapted for coöperation with said die 80 first named, means for moving said head axially, and means comprising a pair of engaging devices having inclined surfaces for limiting the movement of said head toward said bed.

21. The combination with a bed provided with a die, of a revolute head provided with a die adapted for coöperation with said die first named, means for moving said head axially, means comprising a revolute device 90 having an inclined surface for limiting the movement of said head toward said bed, and a revolute worm shaft for turning said device.

In testimony whereof I have hereunto set 95 my name this 23rd day of January, 1918.

TRACY V. BUCKWALTER.
